UNITED STATES PATENT OFFICE.

EDWARD W. JEFFCOTT, OF PLAINFIELD, AND ROBERT C. JEFFCOTT, OF SOMERVILLE, NEW JERSEY, ASSIGNEES TO THE COTT-A-LAP COMPANY, OF SOMERVILLE, NEW JERSEY, A CORPORATION OF NEW JERSEY.

DESIGN FOR A FLOOR-COVERING.

48,637.

Specification for Design.

Patented Feb. 29, 1916.

Application filed December 13, 1913. Serial No. 806,638. Term of patent 7 years.

To all whom it may concern:

Be it known that we, EDWARD W. JEFFCOTT and ROBERT C. JEFFCOTT, citizens of the United States, said EDWARD W. JEFFCOTT residing at Plainfield, in the county of Union, State of New Jersey, and said ROBERT C. JEFFCOTT residing at Somerville, in the county of Somerset and State of New Jersey, have invented a new, original, and ornamental Design for Floor-Coverings, of which the following is a specification, reference being had to the accompanying drawing, forming part thereof.

The figure is a plan view of a portion of floor-covering, showing our new design.

We claim—

The ornamental design for a floor covering, as shown.

EDWARD W. JEFFCOTT.
ROBERT C. JEFFCOTT.
